UNITED STATES PATENT OFFICE.

PETER E. CRADY, OF BURLINGTON, VERMONT.

INDIVIDUAL FILTER.

1,333,011.

Specification of Letters Patent.

Patented Mar. 9, 1920.

Application filed December 7, 1917. Serial No. 206,010.

To all whom it may concern:

Be it known that I, PETER E. CRADY, a citizen of the United States, residing at Burlington, in the county of Chittenden and 5 State of Vermont, have invented new and useful Improvements in Individual Filters, of which the following is a specification.

This invention relates to filtering devices intended for individual use and is especially 10 designed for the use of travelers.

An object of the invention is to provide a device of the above character which is simple in construction, compact in form and capable of being conveniently carried in the 15 pocket.

To this end the invention consists of a filter embodying a pair of detachable sections telescopically arranged, one of which is provided with a mouth piece, each of the 20 said sections being provided at their outer ends with permanently attached screens, while their opposed or inner ends are provided with removable screens, the said sections having the space between the screens 25 filled with a filtering element preferably in the form of charcoal. The removable screens are each composed of a ring with a fine wire mesh secured to one edge thereof and a loop also secured to the rings for the 30 purpose of providing for the convenient removal of the screens, the said screens being held in position within the tubular members by screws or other fastening devices passing through the said members and engaging 35 the rings.

The invention further consists of the following novel combinations and arrangement of parts, to be hereinafter more fully described and illustrated in the accompanying 40 drawings, in which:

Figure 1 is a perspective view of a filter embodying the present invention.

Fig. 2 is an elevation of the same with the sections supported.

Fig. 3 is a longitudinal sectional view with the parts in the position shown in Fig. 1.

Fig. 4 is a detailed perspective view of one of the removable screens and

Fig. 5 is a view of the form of hook preferably employed for removing the screens.

Referring to the drawings in detail, wherein like characters of reference denote corresponding parts, the improved filter is

shown as comprising a pair of telescopically arranged sections 10 and 11, one end of the section 11 being threadedly received within the adjacent end of the section 10 as shown at 12, while the opposite end of the said section 12 is formed with a mouth piece 13. 55

Each of the sections 10 and 11 is provided at opposite ends with permanently secured screens 14 and 15, the former being positioned an appreciable distance from the mouth piece 13, while the latter is preferably 60 located adjacent the outer end of the section 11. Each of the sections 10 and 11 is also provided with screens 16 and 17, which are secured to rings 18 and are of a diameter 65 to fit within the inner part of the sections. 70 The screens 16 and 17 are located adjacent the inner ends of the sections 10 and 11 and are preferably held in position by means of set screws 19 passing through the tubular sections and engaging the rings, or by other 75 fastening devices. Such fastenings however may be dispensed with.

Each of the screens 17 and 18 is provided with loops 20, which are secured to the rings and extend diametrically across the 80 screens to provide means for engagement with a hook 21 or other instrument to facilitate the removal of the screens from the tubular members. The space between the screens 14—16 and 15—17 is filled with charcoal or other suitable filtering element, so 85 that water passing through the tubular members will be filtered.

By forming the device in the manner shown and described, the two sections may 90 be readily disassociated and the screens 16 and 17 removed for the purpose of thoroughly cleaning the filter and maintaining the same in a sanitary condition. The filter is of such size and shape as may be conveniently carried in the pocket either in an 95 assembled or disassembled position.

Various changes may be made in the form, proportion and minor details of construction of the device and the right is reserved to 100 make such changes.

Having described the invention what is claimed is:

A filter embodying a portable member formed of two sections telescopically arranged, a mouth piece formed on one of said sections, an end screen secured in the outer end of each of said sections, a screen posi- 105

tioned in the adjacent ends of each of said sections, a ring carried by each of the last mentioned screens, fastening devices extending through said sections and engageable with said rings to removably hold them in position, diametrically extending loops secured to the outer face of each of the last

mentioned screens for detachable engagement with an instrument for removing said screens and a filtering element located between the screens of each section.

In testimony whereof I affix my signature.

PETER E. CRADY.
